UNITED STATES PATENT OFFICE.

MORTIMER BYE, OF INDIANAPOLIS, INDIANA, ASSIGNOR TO THE ELI LILLY AND COMPANY, OF INDIANAPOLIS, INDIANA, A CORPORATION OF INDIANA.

SYRINGE.

1,174,673.

Specification of Letters Patent.

Patented Mar. 7, 1916.

Application filed June 29, 1914, Serial No. 347,853. Renewed September 10, 1915. Serial No. 50,095.

To all whom it may concern:

Be it known that I, MORTIMER BYE, a citizen of the United States, residing at Indianapolis, Marion county, and State of Indiana, have invented and discovered certain new and useful Improvements in Syringes, of which the following is a specification.

My invention relates to hypodermic syringes and its object is to provide a device of this class in which all the parts that come in contact with the liquid to be injected may be made of glass so that the article will be entirely antiseptic; in which the closure for normally sealing the liquid contents within the syringe barrel may be displaced to permit the discharge of the contents without the necessity of breaking such closure or projecting the needle through the same, and in which the device is placed in condition ready for injection of the contents by a simple manipulation of the needle.

With these objects in view my invention is embodied in preferable form in the device hereinafter described and illustrated in the accompanying drawings.

In these drawings, Figure 1 is a side view in elevation of the device drawn to the same size as that of the syringe, Fig. 2, a central vertical section enlarged beyond the size of the syringe; Fig. 3, a cross section on the line 3—3 of Fig. 4, and Fig. 4, an enlarged detail vertical section of the lower end of the syringe barrel.

In these drawings, 1 is the barrel of the syringe and 2 the plunger thereof. Both are made of glass. The liquid sufficient in amount for a single hypodermic injection is placed within the barrel and is adapted to be contained therein until the injection is to be made, the barrel being tightly sealed by the enlarged head of the plunger and the closure at the other end of the syringe. The lower end of the barrel is reduced and tapered to form an extension 3, in which is formed a restricted passageway 4, leading from the interior of the barrel to a valve chamber 5, which is formed by the wall of a hollow cap 6. This cap is preferably of metal to obtain strength and is adapted to

be cemented on the tapered surface of the extension 3, its upper end abutting against the shoulder 7, formed on the exterior of the barrel at the junction of the main portion of the barrel with the extension. A movable closure consisting of a valve 8 is placed in the valve chambers and this valve is also of glass or other antiseptic material and is preferably spherical in form. A curved seat for the valve is provided in the lower end of the extension 3, whereby said valve is adapted to snugly fit against the outlet end of the passageway 4 and thus close said passageway against the escape of liquid, whenever the valve is pressed against said extension. The cap 6 is threaded interiorly and is engaged by the threads of a needle 9 which is provided with a central longitudinal channel 10 as is usual and which by means of the screw threads is longitudinally adjustable with respect to the cap 6. The end of the needle that is enclosed within the cap is provided with a head which is adapted to bear against the ball valve 8 and when the needle is screwed inwardly as shown in Fig. 2, it will force the valve against its seat in the extension 3, thus closing the passageway 4 and preventing the escape of liquid from the interior of the barrel. The surface of the head of the needle which is adapted to bear against the valve is provided with radial grooves 11 which permit the liquid to pass beneath the ball valve, when the latter is released from its seat against the end of the passageway 4.

The under side of the head of the needle is adapted to closely seat against the lower end wall of the cap. To insure a close joint, a sealing gasket 12 may be provided on the underside of the needle head, although the close joint may be otherwise obtained as by a beveled edge. The needle is provided with a knurled surface 13 beyond the extremity of the cap 6 so that the needle may be readily grasped and turned in order to place the device in operative condition. This knurled portion terminates in a shoulder 14 against which presses the end of a suitable sheath 15, which serves as a protecting cover for the

needle. This sheath may be made of gelatin, celluloid, metal or other material.

The operation of the device is as follows:—The needle is normally projected inwardly as far as it will go, thus holding the valve 8 tightly against the seat in the lower end of the barrel and closing the outlet therefrom, so as to prevent the escape of the liquid contents of the syringe. When it is desired to inject the contents, the knurled portion of the needle is grasped by the hand of the operator and given a few turns which will serve to move the needle outwardly carrying its head down upon the inner face 10 of the cap 6, to make a tight joint and thus prevent the escape of liquid around the threads, and at the same time releasing the pressure on the ball valve which is thereupon free to move within its chamber. The operator then removes the sheath from the needle and the contents may be discharged through the needle by forcing the plunger inwardly which action carries the liquid 20 through the valve chamber and around the valve and through the grooves 11 into the central passage-way of the needle. It will be seen that with this construction the liquid contents are kept out of contact with any metallic parts until the injection is to be 30 made and that during the operation of the device the only metal with which the contents come in contact is that of the cap and needle. In many hypodermic needles now in use a construction is provided whereby a 35 diaphragm or other temporary closure must be broken by the projection of the needle therethrough. In such devices there is danger of particles of the ruptured membrane or other closure becoming mingled 40 with the contents of the syringe and either stopping the needle passageway or being forced through the needle into the patient. The present invention avoids such objections since the closure is a permanent non-breakable valve.

Having thus described my invention, what I claim is:

1. A syringe having a liquid containing body, said body having an outlet leading 50 therefrom, a member permanently attached to said body and having an outlet passage-way, means forming a chamber between said body and said member, a movable valve 55 separate from said body and member and mounted between said parts in said chamber and adapted to close said outlet and means for adjusting said member toward and from the liquid containing body to force the valve against the outlet seat and to release it 60 therefrom.

2. A hypodermic syringe having a liquid containing body, a hollow needle adjustably attached to said body, a movable closure member between the inner end of the needle

and said body and separate from both parts 65 and adapted to control the communication between the same and movable into and out of closing position by the adjustment of said needle.

3. A hypodermic syringe having a liquid 70 containing body, said body having an outlet therefrom, a permanent movable valve adapted to close said outlet and an adjustable needle bearing against said valve and operable to force the same into closing position 75 and to release the valve to permit the liquid to be forced through the outlet, substantially as described.

4. A hypodermic syringe having a barrel, a hollow member secured to one end of said 80 barrel, a valve mounted within said hollow member and adapted to close the outlet from said barrel, an adjustable hollow needle having a head projecting within said hollow member and adapted to bear against 85 said valve whereby when said needle is moved inwardly, the valve will be forced to closing position and when the needle is moved outwardly the valve will be released to permit the contents to be discharged from 90 the barrel into the needle, substantially as described.

5. A hypodermic syringe having a liquid containing body, a movable valve for the outlet thereof, an adjustable hollow needle 95 adapted to press against said valve to close the outlet and to release said valve to open the outlet, said needle having means to seal the space around the needle against the escape of liquid when the needle is moved to 100 releasing position, substantially as described.

6. A hypodermic syringe having a single liquid containing barrel with imperforate walls except for the outer end through which the plunger is inserted and the discharge end containing the discharge orifice, a plunger in said barrel, a hollow needle attached to said barrel, a movable closure member between the inner end of the hollow needle and the outlet from said barrel 110 and separate from both parts and adapted to control the communication between said barrel and said hollow needle, and releasable means for normally pressing said closure member into closing position against 115 the barrel outlet, substantially as set forth.

7. A hypodermic syringe comprising a barrel with imperforate sides, a plunger therein, a hollow needle attached to said barrel, a movable closure member between 120 the inner end of the needle and the discharge outlet of the barrel, and means for retaining said movable closure member in closing position against the barrel outlet, said barrel, plunger and closure member 125 being each formed of aseptic and chemically resistant material, whereby said syringe is adapted to serve as a container for

serums and such like medicinal products and in which such products may be stored and dispensed without contact with septic substances and are also adapted for use 5 without exposure, substantially as set forth.

In witness whereof, I have hereunto set my hand and seal at Indianapolis, Indiana,

this 9th day of June, A. D. nineteen hundred and fourteen.
